UNITED STATES PATENT OFFICE.

FRANCIS HODGKINSON, OF SWARTHMORE, PENNSYLVANIA, ASSIGNOR TO WESTINGHOUSE ELECTRIC AND MANUFACTURING COMPANY, A CORPORATION OF PENNSYLVANIA.

CONDENSER.

Application filed August 4, 1921, Serial No. 489,893. Renewed January 22, 1926.

To all whom it may concern:

Be it known that I, FRANCIS HODGKINSON, a subject of the King of Great Britain and Ireland, and a resident of Swarthmore, in the county of Delaware and State of Pennsylvania, have invented a new and useful Improvement in Condensers, of which the following is a specification.

My invention relates to surface condensers and it has for an object the provision of apparatus of the character designated which shall deliver non-condensable fluids to the non-condensable fluid-withdrawal means at a low temperature and specific volume, and which shall, at the same time, deliver to the hot well condensate at a high temperature. These and other objects and advantages of my invention are attained by the structure hereinafter described and illustrated in the accompanying drawing in which

Fig. 1 is a transverse sectional view of a preferred embodiment of my invention taken on the line I—I of Fig. 2;

Fig. 2 is a longitudinal sectional view thereof taken on line II—II of Fig. 1 and

Fig. 3 is an enlarged fragmentary view of a portion of the section shown in Fig. 2.

Surface condensers of the so-called radial flow type commonly comprise a shell in which a circular nest of cooling tubes is eccentrically disposed with respect to a semi-circular bottom of the condenser shell and through which cold water is circulated to maintain the tubes at a relatively low temperature. The fluid to be condensed, hereinafter for distinction and brevity called steam, is usually received at the upper portion of the shell and flows through the nest of cooling tubes from the steam passages which substantially surround the tube nest, the condensate being extracted at a point adjacent the bottom of the shell. The non-condensable fluids, hereinafter for distinction and brevity called air, which appear in the condenser are usually extracted through an air off-take, the inlet of which is disposed well within the nest of tubes, thereby causing a flow of the steam radially through the cooling tube nest toward the inlet of the air off-take member. Condensers of this type possess the distinctive advantage of providing a heat transmitting surface of high efficiency by reason of the large entrance area presented to the steam enter-

ing the tube nest and further because of the uniformly short path of travel over the cooling tubes to the air off-take. This arrangement also insures there will be no appreciable variation in pressure between the steam inlet and the point of complete condensation.

Efficiency in the operation of condensers demands in addition that the energy expended in the withdrawal of the non-condensable fluids shall be reduced to a minimum. This result is most readily accomplished by reducing the volume of the fluids necessary to be handled by the air-removal means prior to delivery thereto. In my improved construction, I effect this result by providing a separated bank of air cooling tubes which are contained in what may be termed an air-cooling chamber. The air-cooling tube bank preferably rises from the bottom of the condenser to well within the tube nest and substantially surrounds the air off-take, the inlet of which is adjacent the upper portion of the air cooling tube bank. Air passages are provided in the partition separating the air cooling compartment and the condensing compartment of the condenser, which passages in a large measure prevent the transfer of heat from the steam and condensate in the condensing compartment to the air in the air cooling compartment.

It will thus be seen that the air leaving the condensing compartment is successively cooled during its passage over the air cooling tubes and through the off-take, the latter preferably extending contiguous to the air cooling tubes. The air delivered to the air pump has a low temperature and specific volume so that a small pump and a lesser quantity of motive power suffices to withdraw the air and other non-condensable fluids from the condenser to a region of atmospheric pressure.

Referring to the drawings for a more detailed understanding of an apparatus embodying my invention, I have indicated at 10 a condenser, having a shell 11 in which there is a steam inlet 12, a hot well 13, tube sheets 14 secured to the shell, and an eccentrically arranged nest of tubes 15 within the shell and secured to the tube sheets. Water boxes 17, joined to the tube sheets and shell are provided in the usual manner.

The tube nest is divided into two groups

of tubes, which, for distinction and convenience in description, are hereinafter designated as condensing tubes 20 and air cooling tubes 21. The air cooling tubes 21 constitute a wedge-shaped group rising from the bottom of the shell and having its base adjacent the shell and above the hot well. The edge of the wedge-shaped group is located well within the tube nest. The condensing tubes 20 surround the air cooling tubes except where the latter are adjacent to the shell 11.

The two groups of tubes are separated by suitable partitions or wall constructions extending the length of the condenser. As shown, these partitions are formed of inclined hollow wall members 22, 23, comprising outer plate members 24 secured to the condenser shell, and inner plate members 25, secured to and spaced from the outer members 24 by suitable spacers 26. The inner plate members 25 are spaced at their lower edges from the shell to form passages 27 and extend upwardly beyond the outer members 24. A baffle 28 is carried by the inner plate member 25 and extends on either side beyond the upper edges of the outer members 24, forming inlet passages 29. The condensing tubes and the air cooling tubes may be said, for the purposes of this specification, to be contained, respectively, in a condensing compartment and in an air cooling compartment.

An air off-take chamber 30, extending the length of the shell, is located centrally within the group of air cooling tubes, and comprises two parallelly spaced plates 31, 32, joined at their lower edges in any suitable manner, as by welding at 33, and open at the upper edges to form an inlet passage 34 at the upper portion of the air cooling tube group. A conduit 35 leads from the air off-take chamber 30 to a suitable withdrawal means. It will be noted that the condensing tubes are spaced from the sides of the shell and form steam delivery passages 37 and 38, communicating with the steam inlet 12, and surrounding the group of condensing tubes.

The hot well 13 contains two partitions 40, 41 which serve to provide three chambers 42, 43, 44, communicating above the partitions. Condensate, collecting in the lower portions of the condensing compartment adjacent partition members 24, is conveyed therefrom by conduits 45 and 46, into the lower portions of the outer chambers 42 and 44, respectively. The condensate collected in the hot well is discharged to a suitable condensate pump through an outlet port 47 located in the bottom of the chamber 43.

Having described the arrangement of an apparatus embodying my invention, the operation thereof is as follows. Steam from a turbine, or other prime mover, is admitted into the condensing chamber through the

steam inlet 12 and passes within the shell in such a manner as to substantially surround the cooling tubes within the condensing compartment. The cylindrical entrance area to the tube nest is enabled to accommodate 70 large volumes of steam readily, and the steam passes radially through the nest of tubes to the passages 29 which are disposed at a substantially central point within the tube nest. The steam is almost completely 75 condensed in the passage over the tubes so that non-condensable gases having a small condensable fluid content pass between the walls 24 and 25 to the lower portion of the air cooling compartment. The air flows upwardly through the air cooling compartment over the cooling tubes which contain first 80 pass cooling water and is further dried and cooled. The condensate dripping from the cooling tubes of the air compartment falls directly into a hot well where it mingles 85 with the condensate from the condensing chambers as will be hereinafter more fully described. The air then enters the inlet 34 of the air off-take 30, passes downwardly 90 between the groups of air cooling tubes and is withdrawn through the conduit 35 by means of any suitable pump.

The condensate collects in the bottom of the condensing chamber adjacent the baffles 24 and is conveyed therefrom to the hot well by means of the pipes 45 and 46 which extend without the condenser shell to a lower portion of the hot well. The provision of the chambers 42 and 44 within the hot well into which the condensate is withdrawn effectively seals the lower portions of the condensing and air cooling compartments so that a direct flow of air or steam therebetween is prevented. The condensate from the condensing and air cooling compartments commingles in the hot well 13 and is withdrawn therefrom through the port 47 by any suitable pump.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a condenser, the combination with a shell having a fluid inlet port and an outlet port for condensate, of a nest of air cooling tubes rising from the bottom of the condenser, a nest of condensing tubes at the sides of and above said air cooling tubes, and partition means defining air passages between said groups of tubes.

2. In a condenser, the combination with a shell having a fluid inlet port and an outlet port for condensate, of a wedge-shaped

nest of air cooling tubes rising from the bottom of the condenser, a nest of condensing tubes at the sides of and above said air cooling tubes, and dividing means defining 5 air passages between said groups of tubes.

3. In a condenser, the combination with a shell having a fluid inlet port and an outlet port for condensate, of a wedge-shaped nest of air cooling tubes rising from and 10 having the base of the wedge contiguous to the bottom of the condenser, a nest of condensing tubes at the sides of and above said air cooling tubes, and partition means defining air passages between said groups of 15 tubes.

4. In a condenser, the combination with a shell having a fluid inlet port and an outlet port for condensate, of a nest of air cooling tubes rising from the bottom of the condenser, a nest of condensing tubes at the sides of and above said air cooling tubes, and dividing means between said groups of tubes 20 comprising passages through which the uncondensed fluids pass from the condensing 25 tubes to the air cooling tubes.

5. In a condenser, the combination with a shell having a fluid inlet port and an outlet port for condensate, of a nest of air cooling tubes rising from the bottom of the condenser, a nest of condensing tubes at the sides of and above said air cooling tubes and arranged within the shell so that a fluid 30 delivery space communicating with said inlet port substantially surrounds the nest of 35 condensing tubes, and partition means defining air passages between said groups of tubes.

6. In a condenser, the combination with a shell having a fluid inlet port and an outlet 40 port for condensate, of a wedge-shaped nest of air cooling tubes rising from and having the base of the wedge contiguous to the bottom of the condenser, a nest of condensing tubes at the sides of and above said air 45 cooling tubes, dividing means between said groups of tubes comprising passages through which the uncondensed fluids pass from the condensing tubes to the air cooling tubes and a non-condensable off-take having an inlet 50 opening at the converging portion of the nest of air cooling tubes.

7. In a condenser, the combination with a shell having a fluid inlet port and an outlet port for condensate, of a nest of air cooling tubes rising from the bottom of the condenser, a nest of condensing tubes at the sides of and above said air cooling tubes, dividing means between said groups of tubes comprising passages through which the uncondensed fluids pass from the condensing tubes to the air cooling tubes, means for withdrawing condensate from space traversed by the condensing tube, and means for withdrawing non-condensable fluids from 60 the space traversed by the air cooling tubes. 65

8. In a condenser, the combination with a shell having a fluid inlet port and an outlet port for condensate, of a nest of air cooling tubes rising from the bottom of the condenser, a nest of condensing tubes at the sides 70 of and above said air cooling tubes, partition means defining air passages between said groups of tubes, means for withdrawing condensate from space traversed by the condensing tubes, means for withdrawing 75 condensate and independent means for withdrawing non-condensable fluids from the space traversed by the air cooling tubes.

9. In a condenser, the combination with a shell having a fluid inlet port and an outlet 80 port for condensate, of a nest of air cooling tubes rising from the bottom of the condenser, a nest of condensing tubes at the sides of and above said air cooling tubes, partition means between said groups of 85 tubes comprising passages through which uncondensed fluids pass from a central portion of the nest of condensing tubes to the base of the wedge-shaped nest of cooling tubes and a non-condensable fluid off-take 90 having an inlet opening at the converging portion of the nest of air cooling tubes.

10. In a condenser, the combination with a shell having a fluid inlet port, a hot well 95 for condensate and a nest of cooling tubes within the shell, of a wedge-shaped air cooling and drying compartment in the shell through which a portion of the cooling tubes extend, the remaining tubes traversing a condensing compartment, partition means between the compartments comprising passages through which the uncondensed fluids pass from the condensing to the air cooling compartment. 100

11. In a condenser, the combination with a shell having a fluid inlet port, a hot well 105 for condensate and a nest of cooling tubes within the shell, of a wedge-shaped air cooling and drying compartment in the shell through which a portion of the cooling tubes extend, the remaining tubes traversing a condensing compartment, partition means between the compartments comprising passages through which the uncondensed fluids pass from the condensing to the air cooling compartment, means for withdrawing condensate from the condensing compartment into the hot well and means for withdrawing non-condensable fluids from the air cooling compartment. 110 115

12. In a condenser, the combination with a shell having a fluid inlet port, a hot well 120 for condensate and a nest of cooling tubes within the shell, of a wedge-shaped air cooling and drying compartment in the shell through which a portion of the cooling tubes extend, the remaining tubes traversing a condensing compartment, partition means between the compartments comprising passages through which the uncondensed fluids 125 130

pass from the condensing to the air cooling compartment, means for withdrawing condensate from the condensing compartment into the hot well, means for delivering condensate from the air cooling compartment to the hot well, and means for withdrawing non-condensable fluids from the air cooling compartment.

13. In a condenser, the combination with a shell having a fluid inlet port, a hot well for condensate and a nest of cooling tubes within the shell, of a hollow wall projecting into the tube nest, and extending the length of and secured to the shell adjacent one side of the hot well, a second hollow wall similarly positioned adjacent the other side of the hot well, a roof member carried by said walls, the walls and roof members enclosing an air cooling compartment, an air off-take having an inlet adjacent the innermost portion of the air cooling compartment and means for causing the uncondensed fluids from the portion of the tube nest without the compartment to enter at the inner ends of the hollow walls and to be discharged at the outer ends thereof into the outer portion of the said air cooling compartment, pass over the tubes therein, and non-condensable fluids to be discharged therefrom at the inner portion of the compartment into the air off-take.

14. In a condenser, the combination with a shell having a fluid inlet port, a hot well for condensate and a nest of cooling tubes within the shell, of a hollow wall projecting into the tube nest and extending the length of and secured to the shell adjacent one side of the hot well, a second hollow wall similarly positioned adjacent the other side of the hot well, a roof member carried by said walls and defining with the hollow walls an air cooling compartment, the space traversed by the cooling tubes without the walls and roof member constituting a condensing compartment, means for withdrawing condensate from the condensing compartment into the hot well, means for draining condensate from the air cooling compartment into the hot well, an air off-take having an inlet adjacent the innermost portion of the air cooling compartment and means for causing the uncondensed fluids from the portion of the tube nest without the air cooling compartment to enter at the inner ends of the hollow walls and to be discharged at the outer ends thereof into the outer portion of the said air cooling compartment, pass over the tubes therein and the non-condensable fluids to be discharged therefrom at the inner portion of the compartment into the air off-take.

15. In a condenser, the combination with a shell having a fluid inlet and a hot well for condensate, of a nest of air cooling tubes rising from the bottom of the shell and over

the hot well, a nest of condensing tubes at the sides of and above the air cooling tubes, means comprising hollow walls for separating said tube nests and forming within the shell an air cooling compartment and a condensing compartment, partition walls dividing the hot well into three chambers communicating above the partitions and conduits leading from the lowermost portions of the condensing compartment into the lower portion of the outer chambers of the hot well whereby the passage of uncondensed fluids between the condensing compartment and the air cooling compartment through the hot well and condensate conveying conduits is prevented.

16. In a condenser, the combination with a shell having a fluid inlet and a hot well for condensate, of a nest of air cooling tubes rising from the bottom of the shell and over the hot well, a nest of condensing tubes at the sides of and above the air cooling tubes, partition means comprising hollow walls for separating said tube nests and forming within the shell an air cooling compartment and a condensing compartment, partition walls dividing the hot well into three chambers communicating above the partitions, conduits leading from the lowermost portions of the condensing compartment into the lower portion of the outer chambers of the hot well whereby the passage of uncondensed fluids between the condensing compartment and the air cooling compartment through the hot well and condensate conveying conduits is prevented, means for draining condensate from the air cooling compartment into the hot well, an air off-take having an inlet adjacent the innermost portion of the air cooling compartment and means for causing the uncondensed fluids from the portion of the tube nest without the compartment to enter at the inner ends of the hollow walls and to be discharged at the outer ends thereof into the outer portion of the said air cooling compartment, pass over the tubes therein and the non-condensable gases to be discharged therefrom at the inner portion of the compartment into the air off-take.

17. In a condenser, the combination with a shell enclosing a condensing space, and a nest of cooling tubes traversing the condensing space and arranged eccentrically to the shell, of a non-condensable fluid off-take extending into said shell and having an inlet located well within the nest of tubes, two pairs of vertically inclined, spaced baffles, one pair on each side of the off-take and converging toward said inlet, a roof over said baffles, the arrangement being such that fluids entering the condenser pass radially over portions of the tubes, traverse the spaces between each pair of baffles, and then pass over the group of tubes included between the baffles to the said inlet.

18. In a condenser, the combination with a shell having a fluid inlet port and an outlet port for condensate, of a nest of air cooling tubes rising from the bottom of the condenser, a nest of condensing tubes at the sides of and above said air cooling tubes and arranged within the shell so that a fluid delivery space communicating with said inlet port substantially surrounds the nest of condensing tubes, the nest of condensing tubes being so arranged that condensate falling from tubes in the upper portion of the nest passes through and contact with the heated fluid in the lower portions of the fluid delivery space and partition means defining air passages between said groups of tubes.

19. In a condenser, the combination with a shell having a fluid inlet port and an outlet port for condensate, of a nest of air cooling tubes rising from the bottom of the condenser, a nest of condensing tubes at the sides of and above said air cooling tubes and so arranged within the shell as to provide a fluid delivery space communicating with said inlet port between the sides of the condenser and the entrance faces of the nest of

condensing tubes, whereby condensate falling toward the bottom of the condenser falls through the lower portions of the fluid delivery passage so as to abstract some of the heat of the condensable fluid, and partition means defining air passages between said groups of tubes.

20. In a condenser, the combination with a shell having a fluid inlet port and an outlet port for condensate, of a nest of air cooling tubes rising from the bottom of the condenser, a nest of condensing tubes at the sides of and above said air cooling tubes and arranged within the shell so that a fluid delivery space communicating with said inlet port substantially surrounds the nest of condensing tubes, the said nest being arranged so that condensate falling from the tubes in the upper portion will fall through the lower portion of the fluid delivery space and partition means defining air passages between said groups of tubes.

In testimony whereof, I have hereunto subscribed my name this first day of August, 1921.

FRANCIS HODGKINSON.
